UNITED STATES PATENT OFFICE.

DAVID M. MACPHERSON, OF LANCASTER, ONTARIO, CANADA.

HAND-TRUCK.

SPECIFICATION forming part of Letters Patent No. 401,506, dated April 16, 1889.

Application filed February 4, 1889. Serial No. 298,650. (No model.)

To all whom it may concern:

Be it known that I, DAVID M. MACPHERSON, of Lancaster, in the Province of Ontario, in the Dominion of Canada, have invented certain new and useful Improvements in Hand-Trucks; and I do hereby declare that the following is a full, clear, and exact description of the same, reference being had to the accompanying drawings, in which—

10 Figure 1 is a side elevation of my improved truck. Fig. 2 is a plan of the same, and Fig. 3 an end view.

My invention has for its object to construct a hand-truck which shall be specially adapted 15 for conveniently removing boxes of cheese, whereby the boxes will require but little handling and not be liable to injury during shipment or delivery.

My invention consists of a truck having two 20 inclined skids supported at one end by a wheeled axle and at the other end by two handles, which bear on the ground, and having a jaw pivoted to the skids, and said jaws connected at the lower end by toggle-bars and 25 a spirally-coiled spring, and side bars secured to the upper part of the jaws and to the skid to which said jaw is pivoted, so that by deflecting the toggle-bars the jaws and side bars will grip the load laid upon the skids, 30 and when released the load will slide gently down the skids without handling.

A A' are inclined parallel skids connected by transverse bars a. The lower ends of the skids are bolted to an axle, B, having ground- 35 wheels B', and the upper ends of the skids are supported by handles C C', secured to the skids at a suitable distance from the lower end and extending downwardly and rearwardly to the ground, whereby the skids and 40 handles form a Y-shaped frame. The load is laid upon the skids, and the skids are of such length as may be desired.

D is a plate having cheeks d d', and provided with longitudinal slots d², if desired, to 45 secure it adjustably to the outer face of the skids and near the axle by bolts d³, and between said cheeks is pivoted a jaw, E, having a claw termination at the upper end to grapple the load. To the end of the jaws below 50 the cheeks is pivotally sleeved a box, e, in

which is secured adjustably by a screw, f, the outer end of two toggle-bars, g g', their inner ends pivoted together through a sleeve, h, to form a knuckle-joint, and said bars connect the jaws E E, so that by deflecting the 55 knuckle-joint by the foot the toggle-bars draw the lower end of the jaws inwardly to move the upper end outwardly when discharging a load, and by a reverse flexion of the toggle-bars the upper ends of the jaws move inwardly, and the claws grapple the load laden on the skids. Above the boxes e the jaws are connected by a spirally-coiled spring, j, which, by endwise contraction, keeps the 60 toggle-bars from accidentally moving into 65 alignment and thereby occasioning a premature discharge of the load.

H H' are spring-bars, one end fastened to the skid and the other end extending past the jaw to which the said bar is riveted. The outer 70 end of the bars H H' is bent inwardly, and the tension of said spring-bars is outwardly to follow the motion outwardly of the jaws. The inwardly-bent end of said bars H H' closes against the end of the lower box or 75 package of the load when the jaws are approached by the operation of the toggle-bars and assists to retain the load; but when the 80 toggle-bars are deflected in the opposite direction the jaws recede and allow the load to slide down the skids, thereby doing away with considerable handling of the pieces.

When the truck is laden, the handles are raised from the ground by hand to about a level position, the skids then assuming an inclination of about forty-five degrees, whereby the wheeler can stand under the skids to wheel the truck and its load from place to place. Previous to wheeling, the wheeler deflects the toggle-bars with his foot, by pressing on the sleeve h, the effect being to cause the jaws E E to grip the load and the spring side bars, H H', to close and resist any tendency of the load to slip, the spiral spring j then keeping the toggle-bars deflected. By 90 a reverse movement of the toggle-bars the jaws and spring side bars will widen apart, and both motions of the toggle-bars can be effected by the wheeler from his position between the handles.

I claim as my invention—

1. The combination, with the parallel skids A A', secured to an axle, B, having wheels B', and provided with handles C C', supporting the skids inclinedly, of the jaws E E, toggle-bars g g', and spring side bars, H H', as set forth, for the purpose described.
2. The combination, with the skids A A', of the jaws E E, toggle-bars g g', boxes e e, and spirally-coiled spring j, as set forth.

3. The combination, with the skids A A', provided with cheek-plates D, of the jaws E E, spring side bars, H H', toggle-bars g g', and spirally-coiled spring j, as set forth.

DAVID M. MACPHERSON.
